UNITED STATES PATENT OFFICE.

LOUIS HOFFMAN, OF DULUTH, MINNESOTA.

SAD-IRON.

1,218,863.

Specification of Letters Patent. Patented Mar. 13, 1917.

Application filed October 9, 1916. Serial No. 124,696.

To all whom it may concern:

Be it known that I, LOUIS HOFFMAN, a citizen of the United States, residing at Duluth, in the county of St. Louis and State of Minnesota, have invented certain new and useful Improvements in Sad-Irons, of which the following is a specification, reference being had therein to the accompanying drawing.

10 This invention consists of certain improvements in sadirons and relates especially to such an iron equipped with means for heating both the iron and water applied thereto for generating steam.

15 The object is to produce a simple and efficient device of this character having certain novel and advantageous features as will appear from the further description of the device and especially pointed out in the claims.

20 In the accompanying drawings forming part of this application and in which like reference characters indicate like parts:

Figure 1 represents a longitudinal vertical section of an iron embodying my invention, and

25 Fig. 2 is a top plan view of same.

1 represents an open topped hollow metal iron having a preferably removable division wall 2 therein and which I have shown as being fastened by screw bolts 3, upon the inwardly projecting shelf 4 formed a short distance above the bottom 5 of the iron and which forms the steam distributing chamber 6 intermediate the division wall 2 and the bottom 5 of the iron.

30 The top of the iron is covered by a suitable plate 7 being removably fastened thereto in any desired manner, as for example, by suitable screw bolts 8, which construction is common in the art.

35 Within the chamber 9 hereinafter referred to as the combustion chamber and which is formed intermediate the division wall 2 and the cover 7 is placed a narrow flat elongated receptacle 10, which receptacle is positioned on an incline longitudinally within the iron, that portion in the forward end of the iron being higher than that at the rear end of the iron. This receptacle is for the reception of 40 water through the pipe 11 and which water normally runs to and remains at the rear end of the receptacle, as indicated at 12.

45 The water inlet pipe 11 acts as a support to the center of the receptacle, and the steam discharge pipe 13 at the forward end of the

receptacle which communicates with the chamber 6 by being screw threaded through the division wall 2 acts as a support to the forward end of the receptacle, whereby the latter is permanently maintained in an inclined position. If desired, other forms of support for the receptacle, either entirely, or as an auxiliary to the pipe connections, may be resorted to.

50 Passing through the rear wall 14 of the iron and adjacent one edge of the receptacle 10 and preferably slightly below same, is a gas pipe burner 15, said pipe leading from any suitable form of gas supply 16, and just adjacent the rear end of the iron being provided with a branch pipe 17 which connects with the burner pipe 18 identical with that upon the opposite side. These burner pipes are provided with suitable numerous perforations 19 through which gas is admitted and burned in the combustion chamber 9. I preferably use two series of such holes, one pointing toward the undermost edge of the chamber 10 and the other pointing downwardly and inwardly toward the division wall 2, thus distributing the heat properly within the iron and against the steam generating receptacle 10.

55 Within the chamber 6 is suspended a steam distributing tube 20, it having an angular branch 22 adjacent the forward end thereof and which is screw threaded within the division wall 2 and abutting the end of the steam supply pipe 3. This pipe is provided with preferably two series of small holes 23, one upon each side of the pipe, its entire length, these being for the even and uniform distribution of steam from the pipe 20 into the chamber 6.

60 Through the bottom 5 of the iron are a plurality of perforations 24 as common in such devices. The water supply pipe 11 passes upwardly through the cover 7 and communicates with a T-connection 25 which is mounted upon the end of the water supply 65 pipe 11. Within the T-connection 25 is a longitudinally reciprocal valve of any desired form and which is well known in the art, the same being opened and closed by reciprocal motion of a protruding stem 27 and which stem in this particular case is made to open a valve when thrust inwardly and to close the valve when thrust outwardly, the latter motion being accomplished by a suitable spiral spring 28, surrounding said stem 70

110

and impinging against the head thereof. An L-shaped lever 29 is pivotally supported at 30 upon one member 31 of the handle 32, the lower finger 33 of which lever is designed to impinge the extreme end of and force inwardly the valve stem 27 when the horizontal end 34 of the lever is raised. The end 34 of the lever 29 operates within an elongated recess 35 formed within the handle 10 32 and having a depending finger knob 36 upon the extreme end thereof protruding below the lowermost edge of the handle 34 becomes readily accessible to the finger of the operator and whereby the water supply to the chamber 10 is conveniently governed. I have shown a horizontal portion 37 intermediate the handle supporting members 31-31 as being united with the cover 7 of the iron through the iron supporting bar 38 15 20 which represents an iron designed to be controlled vertically by a mechanism like or similar to that disclosed in my patent dated Aug. 29, 1916, No. 1196112, but it is evident that this invention is equally applicable to 25 a strictly hand sadiron. While I have shown the heat element as being that of gas, it is evident that by slight modification of construction, the necessary heat may be produced by electricity and that without departing from the novel features of my invention, as it is well known that both gas 30 and electricity have been used for like purposes.

Any number of openings or holes, as indicated at 39 may be formed through the side or end walls of the iron as required for admitting air for proper combustion of the gas therein.

In the operation of the device, gas is first 40 turned on by proper adjustment of the various valves and regulators common in the art and ignited. When the iron is sufficiently heated and the operator ready to proceed with his work, just sufficient pressure is 45 brought against the finger tip 36 to admit the proper amount of water into the chamber 10 and wherein any portion of the water not immediately generated into steam, will by gravity collect in the rear lowermost portion 50 of the receptacle 10 and in no event permit water to pass into the chamber 6 and out through the bottom of the iron unless it is positively desired to do so and in which case a larger volume of water may be admitted 55 to the receptacle for the purpose, or the rear end of the iron elevated sufficiently to empty

the water therein through the pipe 13 into the chamber 6.

Thus it is evident I have provided a comparatively simple and efficient means whereby a heated sadiron may be readily supplied with either steam or water, as desired, or operated independently of either.

Having thus described my invention what I claim and desire to secure by Letters 65 Patent, is:

1. In combination, a two chambered sadiron, an inclined steam generating receptacle in the uppermost chamber, and having a water supply connected therewith, a steam 70 or water distributing perforated pipe within the lowermost chamber and connected with the steam generating receptacle, heating means within the iron and above the lowermost chamber whereby both the 75 receptacle and iron are heated and means for controlling the water and heating elements, substantially as described.

2. In combination, a two chambered sadiron, an elongated steam generating receptacle in the uppermost chamber and having a water supply connected therewith, a steam or water distributing perforated pipe within the lowermost chamber and connected with the steam generating receptacle, heating 80 85 means intermediate the lowermost chamber and the receptacle whereby both are heated, means whereby either water or steam or a mixture of both may be admitted to the lowermost chamber, and means for controlling the water and heating elements, substantially as described.

3. The combination with a sadiron having a heating chamber and a distributing chamber, of a steam generating receptacle 95 within the heating chamber and having means whereby either steam, water or both may be discharged therefrom into the distributing chamber, parallel heating pipes extending within the heating chamber and 100 substantially intermediate of the generating receptacle and the upper wall of the distributing chamber whereby an equal distribution of heat is accomplished, and means for controlling the water and heating elements, substantially as described.

In testimony whereof I hereunto affix my signature in the presence of two witnesses.

LOUIS HOFFMAN.
